Re: No. 12,812

Isaac Orr of Washington City, and C. Sitter, Patent, January 20, 1836.

The schedule referred to in this Letter, Patent and making part of the same containing a description in the words of the said Isaac Orr, himself of his improvement in the air-tight stove and in the management of fuel, heat.

To all persons to whom these presents shall come Isaac Orr citizen of Washington City and District of Columbia and Testifying as follows:

Be it known that I the said Isaac Orr have invented, executed and applied to use, a new and useful art or method or process of lessening the consumption and of increasing and otherwise improving the effects of fuel specified in the words following viz. This art or method or process of lessening the consumption and of increasing and otherwise improving the effects of fuel consists in, in making and keeping the stove or other fire place so nearly air-tight at the passages both to and from the fire as to have the combustion of the fuel always dry and combustible, and however great in quantity in the entire, immediate and ready control of the operator, so that he can raise it at once to any required degree of power, put it out or reduce it to any required or useful degree of slow combustion, so that he can by the same means, that is by making and keeping the stove permanently and especially air-tight, and also by giving it the proper size, have any required quantity of fuel, ready heated, dried, charred or reduced to charcoal for immediate use, without having separated it at all from the living fire, which is to kindle it or from the current of air passing through the stove; so that he can thus retain the fire merely alive, for a night or more or less, for the purpose of kindling without burying or dipping with ashes, or with any other merely temporary or accidental material, so that he can thus retain the fire and air in the stove or fire place at pleasure, causing the fine air and smoke to circulate within, ascending from the fire and descending to and through it repeatedly thus consuming their carbon and oxygen rapidly, receiving caloric from the fire and transmitting it repeated by the top and sides of the stove or fire place, which for-

this purpose should be chiefly, or wholly composed of sheet iron or other thin material, so that he can thus and by means of having the stove made of greater or less capacity in comparison of the amount of fire, make its heat or warmth mild or temperate in proportion to the greatness of such capacity or intense and radiating in proportion to the smallness of such capacity, and so that he can thus produce a uniformity in the combustion of fuel, and in the communication of heat, greater than by any stove known with less trouble in the management and with greater safety, when the fire is left to itself. The means by which the requisite tightness is most simply and readily obtained is by making the openings to and from the fire, as few and small as is consistent with convenience and as tight as is requisite to answer the purpose desired, the sliding door being made and used at the entrance or entrance to the fire, both for the purpose of tightness and of facility, safety and exactness in regulating the draft and closing up the fire though in the process of this specification any other convenient door may be used. The axis of the damper should be aside from the centre of the area of the damper for the purpose of giving way readily before the force of occasional though in no way dangerous explosion, occasioned by hydrogen gas. When anhydrous or other fuel of rather difficult combustion is to be used, the method of making the heat or warmth communicated from the stove or fire place mild or temperate and of keeping the fire alive in case of reducing or lowering the degree of combustion is, to put a vessel of cast iron or other material lined or otherwise to contain the coal or fuel inside of the stove or fire place, and at such a distance from the sides of the stove or fire place, that the smoke and air may circulate freely between said vessel and said sides, said vessel communicating both at top and bottom by openings, with said air and smoke, which are thus permitted to pass repeatedly through the fuel in said vessel for the purpose of consuming their carbon and oxygen, and of repeatedly receiving and conveying caloric from the fire to the top and sides of the stove or fire place, said vessel also being made to communicate at bottom with the air of the room, through a double wheel gate or through a sliding or other door and any other gate, by which means in either case the draft may be stopped increased or otherwise regulated at pleasure.

The double wheel grate also serving the purposes of a grate, a poker and a cleaner. The double wheel grate is composed of two similar wheels, flat or otherwise though the inverted conical wheels are believed to be the best. The two wheels being made with corresponding openings, which openings may in their length radiate from the centre of each wheel, be made concentric with it; or otherwise though the concentric openings are believed to be the best, one of the wheels is to be fixed at or near the bottom of the stove or fire place and the other wheel is to be made so as to revolve on the inside of the former wheel by means of an axis fixed to the inner wheel said axis passing movably through the centre of the outer wheel; said wheels to be so constructed that the openings of the outer wheel will be wider than those of the inner so that small bodies passing through the inner wheel will not stick in the openings of the openings of the outer wheel, the openings of the two wheels being made of such form, position and comparative sizes, that in one position of the two wheels, the openings of one will coincide with the openings of the other, in another position, the openings of one will be closed by the solid parts of the other and in the intervening position, the openings through both wheels will be more or less diminished or enlarged by which diminution or enlargement the draft is regulated.

I well call, in managing the stove or fire place the damper should be opened only just so much more or less than the door, that smoke from the fire will not come into the room. An excess of opening of the door brings the smoke into the room, an excess of opening of the damper carries off the heat, and wastes the fuel. Sudden explosions or puffs may be usually prevented by an excess of opening of the damper in which case only it is believed to be expedient or free from loss. When coal is used smoke for the requisite trial may be made by a bit of wood or other smoking or odoriferous material.

2. In making an opening behind or near the bottom of the air tight stove or other air tight fire place, directly from the room into the main flue or chimney into which main flue the flue of said stove or fire place enters, the opening to be used as a ventilator; for letting the air of the room go off it being hastened by the draft of the main flue or

chimney without passing through the stove or fire place, by which means much heat is saved. With the exception of said opening and the fire of the stove or fireplace, the separation composed of brick, sheet iron or other material between the room and the main flue should be entirely airtight to prevent the escape of the warm air of the room, the pressure of which against said separation or partition is at times very powerful. Said opening should be large or small according as the room is to be often or seldom ventilated, from five to nine inches square is believed to be sufficient. Said opening is closed by a light shutter or cover of good paste board or other material, which shutter is made so as to turn on its lower edge, having an obstruction (a slender spring is best) which will prevent it from opening too far so that the outward pressure of the warm air of the room may close it, or said shutter may be suspended on hinges or otherwise, being easily movable, and so constructed that when said shutter hangs freely, it will close the ventilator so as to be airtight or nearly so, and that when it is pressed inward toward the room it will easily open, so that when a door of the room is shut quickly, the ventilator may open more or less, and the smoke may not be drawn by said door from the stove or fire place into the room, and so that, a sudden gust coming down the main flue or chimney may find a brief and partial entrance by the ventilator instead of flowing through the stove or fire place, thus carrying the smoke with it into the room. When the air of the room requires to be changed in the day time, when the room should be warm the fire should be a little increased and the ventilator opened wide for fifteen or thirty minutes more or less. It is usually however quite sufficient to keep it open during the night when much warmth in the room is not required, and even then it is usually enough and most useful to open it partially more when the weather is warm, less when it is cold, and if it is desired still further to increase and extend the effect of the fire, the chimney or main flue itself may be made of sheet iron or other thin material, having a damper chain built with each of the higher floors of the house. In this way less room is occupied and the warm air and smoke being longer detained and circulating in the main flue, the upper rooms may often be sufficiently warmed by the fire below. In this case

there should be a ventilator into the main flue from each of the rooms, which ventilators should be capable of being rendered completely air tight; air tight stoves if needed may also be attached to the same main flue in all the rooms which are above and below each other.

For the purpose of increasing the same effect but more especially for preventing the wind from blowing down chimney which is not entirely protected by the air tight stove, though it is more so than by any other fire place the top of the main flue or chimney should be protected by a simple conical pyramidal or other simply formed cap, of sheet iron or other light material made to move up and down but not to revolve, having a rare connected with it with a weight on the windward end of the vane, and so constructed that said weight will always bring the windward side of the cap nearer the top of the main flue or chimney than the leeward side of the cap. When the cap turns with the vane, said weight is not used, but the vane and cap are so constructed that the vane when turned by the wind carries the lower side of the cap around with it. By means of an apparatus composed of levers and these connecting wires or rods, somewhat in the manner of house lifts said cap is raised and lowered at will from any required position to a height or otherwise regulate the passage of the smoke from the top of the main flue or close it entirely if desired, in which last case the non revolving cap is believed to be best, the other the most simple for other purposes -

1. that I claim as my own invention or discovery and not previously known in the above described art or method or process, i. e. The whole combination of new and old particulars in the construction manufacture and use of the whole apparatus above described, and for attaining the objects specified above.

2. The combination of new and old particulars in the construction, manufacture and use of the air tight stove or fire place, as above described, and for attaining the objects above specified in connexion therewith.

3. The combination of new and old particulars in the construction manufacture and use of the main flue, as above described in connexion with the cap and ventilators also described and for attaining the objects, &c.

Combination of new and old particulars in the construction manufacture and use of the main flue also described in connexion therewith.

4. The combination of new and old particulars in the construction manufacture and use of the smoke cap, also

- described and for attaining the object specified in connection therewith -
6. The new art or process of constructing and using the simple cap having nothing between it and the ordinary main flue or chimney so as to move up and down or so as to revolve with the vane, having its windward edge all the time very near to the top of the chimney -
7. The new art or process of constructing and using the ventilator so that it will communicate directly with the main flue, or chimney, giving way before a slight pressure from without the room and closing before a slight pressure from within it, as above specified -
8. The new art or process of heating, drying or charing the fuel beforehand in any required quantity without separating it at all from the fire that is to kindle it, or from the current of air passing through the fire place, and of retaining the fire merely alive as in the case of raking it in the manner and for attaining the objects above specified -
9. The new art or process of causing the same air and smoke to circulate in the stove or fire place, so as repeatedly to pass to and through the fire in the manner, and for attaining the objects above specified. This may be much more imperfectly done without the damper, the removal of which cannot therefore invalidate my claim -
10. The new art or process of obtaining different kinds of temperature in a room, as it regards the mildness, and more exciting radiation of that temperature in the manner, and by the means above described, especially useful for consumptive people -
11. The construction, manufacture and use of the sliding door as the principal door or doors of a stove or fire place as above described, and to attain the objects above specified -
12. The construction, manufacture and use of the damper, having its axis aside from the centre of its area, as above described, and for attaining the object above specified - viz. preventing any unpleasant effect from puff, or explosion -
13. The construction, manufacture and use of the double wheel, grate as above described and for attaining the objects above specified -
14. The construction, manufacture and use of the coal burner or inner useful for containing the fuel as above described and for attaining the purposes above specified -
15. The new and peculiar combination of the new and old particulars in the construction, manufacture and use

9331X

207.

of the particular air tight stove exhibited in the Drawing and Model accompanying this Specification. There are other new particulars and new combinations which I do not, and do not mean to abandon but to await if necessary the decision of those tribunals to whom such questions are to be finally referred.

Witness,

W. Cooper Jr.
